TABLE LIGHTER

Curt Heuckeroth, Steinbach, near Michelstadt (Odenwald),
Germany, assignor to Rowenta Metallwarenfabrik
G.m.b.H., Offenbach (Main), Germany

Filed Oct. 15, 1964, Ser. No. 82,184

Term of patent 14 years

(Cl. D48—27)

FIG. 1

FIG. 2

FIG. 3

FIG. 4

FIG. 5

FIG. 6

FIG. 1 is a top view of a table lighter showing my design;

FIG. 2 is a left-hand elevational side view of the table lighter;

FIG. 3 is an elevational front view of the table lighter;

FIG. 4 is an elevational right-hand side view of the table lighter;

FIG. 5 is a bottom view of the table lighter; and

FIG. 6 is an elevational rear view of the table lighter.

The horizontal lines are indicative of shallow grooving in FIGS. 2, 3, 4 and 6.

I claim:

The ornamental design for a table lighter, as shown and described.
